UNITED STATES PATENT OFFICE.

ALBERT G. HANSON, OF WESTHAVEN, CONNECTICUT, ASSIGNOR TO LEWIS I. DE MERITTE, OF LEE, NEW HAMPSHIRE.

PUZZLE.

SPECIFICATION forming part of Letters Patent No. 695,455, dated March 18, 1902.

Application filed July 13, 1901. Serial No. 68,125. (No model.)

To all whom it may concern:

Be it known that I, ALBERT G. HANSON, a citizen of the United States, residing at Westhaven, in the county of New Haven and State 5 of Connecticut, have invented certain new and useful Improvements in Puzzles, of which the following is a full and complete specification, such as will enable those skilled in the art to which it appertains to make and use 10 the same.

The object of my invention is to provide a puzzle of a new and improved form of exceeding intricacy, but of cheap construction.

To such end the same consists, in substance, 15 of a wire base-piece provided with end portions turned inward toward one another, one provided with a small and the other with a large loop, the radii of which are at right angles to one another, a wire center piece provided with a rear loop secured at the forward central portion in the small loop of the base portion and of such size as to extend below the large loop of such base portion, such center piece having an end wire extending up- 20 ward through the main or large loop of the base-piece, over the forward edge thereof, down through its own loop, and thence backward to a point adjacent to the rear of the base-piece, and a loop of chain or flexible 25 cord.

In the accompanying drawings, forming 30 part of this specification, in which like letters of reference designate corresponding parts in the several views, Figure 1 is a view in perspective of my improved puzzle, showing the chain-loop in position thereon. Fig. 2 is a like view thereof in the first position; Fig. 3, a view in the second; Fig. 4, a view in the third; Fig. 5, a view in the fourth; Fig. 6, a view in the fifth; and Fig. 7, a view in the sixth and last position, the dotted lines showing the chain-loop in the act of dropping from the end wire of the center piece.

My improved form of puzzle is formed of 45 brass or other suitable metallic wire and consists of a base-piece 8, bent upon itself at either end toward the center at 10 and 11 and provided at the end adjacent to 11 with a small vertical ring or loop 12 and at the end 50 adjacent to the loop 10 with a large horizontal loop 13. Secured at one side in the small

loop 12 is the horizontal loop 14 of the center piece 9, the forward split side of which loop extends under the edge of the horizontal loop 13, and up through the loop 13 extends one 55 end of the wire out of which the loop 14 is formed, which bends thence into a vertical loop 15 and down through the loop 14, and thence toward the loop 10, ending at 16, just a little beyond the rear edge of the loop 13. 60

The reference-numeral 17 designates an endless flexible loop, usually of the form of a metallic chain of small links. The chain 17 being in position upon the base-piece, having the end loops 10 and 11 passing around 65 such wire, as shown in Fig. 1, such base-piece is lifted into the position shown in Fig. 2, with the loop 10 uppermost, and by taking hold of the chain 17 at 19 by deft manipulation the other end 20 of such chain-loop is allowed to drop by gravity through the loop 13 and down over the loop 15, as shown in such Fig. 2. The device is then shifted into the horizontal position shown in Fig. 3, and the loop 20 is passed down toward the loop 10 and 70 around the end 16, when the parts will be in the position shown in Fig. 5, when, by passing the chain up around the loop 20 into the position shown in dotted lines in Fig. 5, if now the device be placed in the upright position shown in Fig. 6 the bight 20 may be turned off from the end wire 16 of the center piece 9, as shown in dotted lines in Fig. 7, when the chain portion or loop 17 will be entirely free from the wire portion of the device and may be again placed in position 75 thereon by a reversal of the process just described.

Having thus fully described my invention, what I claim as new, and desire to secure by 80 Letters Patent, is—

1. A puzzle consisting of a base-piece of wire bent upon itself provided with an end loop, a center piece secured to the other end of the base-piece having a loop lying in the 85 same direction as the loop of the base-piece, the end wire of which loop extends up through the loop of the base-piece down through the loop of the center piece and under the loop of the base-piece, and an endless loop of flexible material, substantially as shown and described. 100

2. A puzzle consisting of a base-piece of wire bent upon itself at both ends and having a large loop formed in one end, and a small loop formed in the other end in a plane at a right angle to the first loop, a center piece having a large loop secured in the small loop, which large loop extends under the large loop of the center piece, and one end of the wire of which center piece extends up through the large loop of the center piece and in a large loop at a right angle to both loops down

through the loop of the center piece and back under the large loop of the base-piece, and an endless loop of flexible material, substantially as shown and described.

15

In testimony that I claim the foregoing as my invention I have signed my name in presence of the subscribing witnesses.

ALBERT G. HANSON.
